SINGLE STRINGER SEPARABLE FASTENER

Louis H. Morin, Bronx, N. Y., assignor of one-half to Davis Marinsky, Bronx, N. Y.

Application April 15, 1942, Serial No. 438,977

14 Claims. (Cl. 24—205)

This invention relates to separable slide fasteners. More particularly, the invention relates to fastening devices of this kind, wherein the complete device is made from a single stringer tape folded centrally to bring double acting scoops, on the end portions of the tape, defined by the fold, into engaging relationship with each other and forming, at the fold of the tape, an end stop limiting movement of the slider in one direction on the fastening device. The novel features of the invention will be best understood from the following description when taken together with the accompanying drawing in which certain embodiments of the invention are disclosed and in which the separate parts are designated by suitable reference characters in each of the views; and in which:

Fig. 1 is a plan view showing one form of fastener made according to my invention with part of the construction broken away.

Fig. 2 is a view similar to Fig. 1 showing only one end of the fastener and showing a modification.

Figs. 3 and 4 are views similar to Fig. 1 showing other adaptations of the invention.

Fig. 5 is a plan view of the central portion of a single tape indicating the folded position of the tape.

Fig. 6 is a view similar to Fig. 5 showing another form of tape construction.

Fig. 7 is an enlarged detail view of a sectional part of a coupled fastener illustrating one form of reversible or double acting scoop which I employ, part of the construction being broken away and in section; and

Fig. 8 is a perspective view of one of the stringer scoops.

In the construction of what is commonly referred to as separable fasteners, it has been the practice to construct the fastener from independent stringers. Quite often, these stringers are coupled together at one end by an end stop coupling which limits opening movement of the stringers. These uses of fasteners are by far more common than the completely separable uses as employed on jackets and in connection with other articles where complete separation of the parts is desirable. Constructing fasteners of the type and kind requiring the end stop coupling, it has been necessary to keep track of the different stringer lengths as produced by machines to reassemble stringers of a common length.

With my improved construction, a single stringer will be produced having either a con-

tinuous row of links thereon, which collectively will form a complete fastener when folded centrally, or the stringer will have arranged thereon, in predetermined spaced relationship to each other, pairs of link sections, so that in severing the stringer tape beyond the limits of said pair of sections, the tape is folded at the space between the link sections in uniting said section to form the fastener. Further, the folding of the tape automatically forms an end stop limiting the movement of the slider in one direction on the fastener and in some instances, the other ends of the link sections may be coupled together to form another end stop. With all forms of construction employed, the stringer tape or the adjacent sections thereof will have links or scoops of the double acting or reversible type to provide interlocking engagement between the links when the stringer tape is folded as stated.

20 In the accompanying drawing, a few adaptations of the invention are disclosed, and in Fig. 1 I have indicated at 10 a fastener formed from a single stringer 11 having links or scoops 12 attached to one beaded edge 13 thereof. In producing the fastener 10, the links 12 are arranged on the tape 11 in a continuous length, as diagrammatically illustrated in Fig. 6 of the drawing, and the tape is folded or curved centrally, as indicated at 14 in forming a closed loop end on the resulting fastener. The free ends of the tape 11 have adjacent end links stops 15 which limit movement of a slider 16 in the direction of said end of the fastener, the folded or looped end 14 forming a stop limiting the movement of the slider in the other direction.

25 In Fig. 2 of the drawing is shown at 17 one end portion of another form of fastener made from a single stringer tape 18 of the general type and kind illustrated in Fig. 5 of the drawing, that is to say, where the links or scoops 19 are arranged in two sections on the tape with a predetermined spacing, as at 20, centrally of the tape 18, this spacing controlling the folding of the tape in the manner illustrated at 21 in Fig. 2 of the drawing. The central part of the tape section 20 crosses the tape ends or what might be termed the link sections of the tapes, as indicated in dotted lines at 22 to form a bridging member 22'. The length of the spacing 20 will be such as to leave a short extension of adjacent beaded edges 23 of the tape, beyond the links, to receive a coupling plate 24, which unites these edges with the crossed central portion 22 of the tape, thus forming a secure and well reinforced end stop, which limits the movement of the slider 25 in one direc-

tion on the fastener 17. The other end of the fastener may be constructed in accordance with the teachings in Fig. 1 of the drawing.

In Fig. 3 of the drawing, I have indicated at 28 another form of fastener made from a single stringer 27 which has a shorter spacing 28 between the adjacent links 29 at the central portion of the stringer tape. With this construction, the other free ends of the tape 27 are joined by an end stop coupling 30 and the slider 31 arranged on the stringer sections of the fastener 28 with the wide end portion 32 of the slider extending in the direction of the end stop produced by the central fold of the tape, differing in this respect from the structure shown in Figs. 1 and 2 where the narrow end of the slider extends in this direction.

Another form of fastener similar to that of Fig. 3 is shown at 33 in Fig. 4 of the drawing, the main difference between the two structures being that a wider spacing is provided centrally of the tape 34 as indicated at 35, in other words, a spacing somewhat similar to that of Fig. 2 but instead of providing an end stop coupling 24, the folded end 36 will be stitched, as indicated at 37 in the operation of attaching the fastener to a support, the wider spacing beyond the end links producing free movement of the needle beyond the end links 38 in this stitching operation. The other end of the fastener 33 will have an end stop 39 similar to the stop 30 and the slider 40 will be arranged in the same manner as the slider 31.

The structure of Figs. 3 and 4 are adapted for uses where separation of ends of the fastener are not desirable, for example, in providing closures for pockets, containers and the like. On the other hand, the structure of Figs. 1 and 2 are adaptable for uses where the fastener is permanently united at one end only. In addition to simply uniting the end of the fastener where the single tape is folded, I also provide a reinforced end stop, the reinforcement constituting an integral part of the tape disposed in a position transversely with respect to the link sections. This type of construction has many practical uses, one of which is installations in trousers where the reinforcement of bottom stop structures is desirable.

In all of the fastener devices illustrated, the links or scoops employed on the single stringer tapes are of what I term the double acting or reversible type and in Figs. 7 and 8 of the drawing I have shown, in detail, one form of link or scoop construction which is suitable for this purpose.

In Fig. 7 of the drawing, 41 represents part of the side sections of a single tape on the beaded edge 42 of which is secured links or scoops 43. Each link or scoop comprises a yoke shaped end portion 44 which engages the beaded edge 42 and extending beyond the beaded edge upper and lower edges of the scoop have V-shaped recesses 45 and V-shaped projections 46. Outer surfaces 47 of the links or scoop are flattened and provided with vertical channels or recesses 48 which open through upper and lower surfaces of the scoop. These channels 48 are adapted to receive rounded ribs 49 which extend into the recesses 45 as will clearly appear from a consideration of Fig. 8 of the drawing.

It will thus be seen from a consideration of Fig. 7 of the drawing, that as the V-shaped projections 46 of one link enter the V-shaped recesses 45 on adjacent surfaces of opposed links, the ribs 49

of the opposed links will enter the recesses 48 of the intermediate link.

With a link construction of this type and kind it will readily appear that the single tapes may be employed in producing the complete fastener as above described by simply folding the tape either centrally of a continuous row of links, or a predetermined space formed between pairs of link sections on said tape. It will, of course, be apparent that the length of the link or scoop sections will govern the length of the resulting fastener. However, each tape length will constitute the complete linkage or stringers of the resulting fastener to be produced, thus dispensing with the necessity of caring for two independent tapes or stringers, as has been the customary practice.

For purposes of description, the opposed series of links or scoops on the single tape will be termed stringer chains in defining the portions of the fastener which are coupled and uncoupled by operation of the slider, or these portions may be termed chain parts.

In the different forms of construction shown, it will appear that the central folded portion of the tape is arranged upon and extends transversely across adjacent ends of the resulting chain formed by folding the tape. This integral transverse tape member not only forms a reinforcement but also produces a pocket, such as those shown at P, P' and P'', into which the end of the slider may pass. It also forms a bridge member which checks the movement of the slider, such as those shown at 22', 28' and 36'.

Having fully described my invention, what I claim as new and desire to secure by Letters Patent is:

1. A separable fastener employing a slider movable along chain parts to couple and uncouple the same, said chain parts comprising a unitary stringer tape with double acting scoops arranged longitudinally of one edge portion thereof, a central fold in said tape, said fold constituting an end stop limiting movement of the slider in one direction on said chain parts formed by the folded portion of the tape, and end stops at the opposite end of said stringer tape from the end carrying the folded portion thereof.

2. A separable fastener employing a slider movable along chain parts to couple and uncouple the same, said chain parts comprising a unitary stringer tape with double acting scoops arranged longitudinally of one edge portion thereof, a central fold in said tape, said fold constituting an end stop limiting movement of the slider in one direction on said chain parts formed by the folded portion of the tape, means in addition to the fold of the tape for reinforcing said end stop, and stop means for the slider on the stringer tape at the end opposite to the folded portion of the tape.

3. A separable fastener employing a slider movable along chain parts to couple and uncouple the same, said chain parts comprising a unitary stringer tape with double acting scoops arranged longitudinally of one edge portion thereof, a central fold in said tape, said fold constituting an end stop limiting movement of the slider in one direction on said chain parts formed by the folded portion of the tape, means in addition to the fold of the tape for reinforcing said end stop, and means at the other end of said chain parts limiting movement of the slider in the other direction.

4. A separable fastener employing a slider movable along chain parts to couple and uncouple the same, said chain parts comprising a unitary

stringer tape with double acting scoops arranged longitudinally of one edge portion thereof, a central fold in said tape forming the chain parts, an end stop limiting movement of the slider in one direction on said chain parts formed by the folded portion of the tape, means in addition to the fold of the tape for reinforcing said end stop, means at the other end of said chain parts limiting movement of the slider in the other direction, and said last named means coupling the chain parts adjacent end links thereon.

5. A fastener of the character described comprising an elongated tape, double acting scoops extending throughout the major portion of the length of one edge of said tape, a central fold in said tape forming two link chains, the links of said chains being adapted to be coupled and uncoupled in forming a slide fastener, a slider movable along the link chains to couple and uncouple the same, the fold of said tape forming a stop limiting movement of the slider in one direction on said chains, and stop means on the free end of said link chains.

6. A fastener of the character described comprising an elongated tape, double acting scoops extending throughout the major portion of the length of one edge of said tape, a central fold in said tape forming two link chains, the links of said chains being adapted to be coupled and uncoupled in forming a slide fastener, a slider movable along the link chains to couple and uncouple the same, the fold of said tape forming a stop limiting movement of the slider in one direction on said chains, an integral reinforcing bridge member arranged transversely over the fold of the chains and stop means for said slider on the end of said link chains opposite to the fold of said tape which forms said stop.

7. A fastener of the character described comprising an elongated tape, double acting scoops extending throughout the major portion of the length of one edge of said tape, a central fold in said tape forming two link chains, the links of said chains being adapted to be coupled and uncoupled in forming a slide fastener, a slider movable along the link chains to couple and uncouple the same, the fold of said tape forming a stop limiting movement of the slider in one direction on said chains, an integral reinforcing bridge member arranged transversely over the fold of the chains, other means reinforcing said folded portion of the tape, and stop means on the end of said slider fastener opposite to said stop formed by the fold in said tape.

8. A fastener of the character described comprising an elongated tape, double acting scoops extending throughout the major portion of the length of one edge of said tape, a central fold in said tape forming two link chains, the links of said chains being adapted to be coupled and uncoupled in forming a slide fastener, a slider movable along the link chains to couple and uncouple the same, the fold of said tape forming a stop limiting movement of the slider in one direction on said chains, and means coupling the other end of the chains adjacent end links thereon.

9. In separable fasteners of the class described, an elongated tape having double acting links arranged and spaced longitudinally of one edge of the tape, a central fold in said tape adapted to arrange the link edges thereof in opposed relationship to each other, the fold in said tape forming of the side portions thereof link chains of a fastener adapted to be coupled and uncoupled and an end stop, and stop means on the opposite ends of said link chain from said end stop formed by said fold.
10. In separable fasteners of the class described, an elongated tape having double acting links arranged and spaced longitudinally of one edge of the tape, a central fold in said tape adapted to arrange the link edges thereof in opposed relationship to each other, the fold in said tape forming of the side portions thereof link chains of a fastener adapted to be coupled and uncoupled, and an end stop, and stop means on the ends of said link chains opposite to the fold in said tape.
11. A fastener of the class described comprising two series of double acting scoops, a single tape supporting both series of scoops, adjacent ends of each series of scoops being spaced apart centrally of the tape, a central fold adapted to arrange the series of scoops in position for coupling and uncoupling one with respect to the other, the folded central portion of the tape forming an end stop at one end of said series of scoops, and means forming an end stop at the other end of said series of scoops.
12. A fastener of the class described comprising two series of double acting scoops, a single tape supporting both series of scoops, adjacent ends of each series of scoops being spaced apart centrally of the tape, a central fold adapted to arrange the series of scoops in position for coupling and uncoupling one with respect to the other, the folded central portion of the tape forming an end stop at one end of said series of scoops, means forming an end stop at the other end of said series of scoops, and the scoops of each series having common interengaging male and female coupling portions on upper and lower surfaces thereof.
13. In separable fasteners employing opposed link chains adapted to be coupled and uncoupled by a slider movable along said chains, a chain forming unit comprising an elongated tape, said tape having two groups of double acting links arranged longitudinally of one edge portion thereof, said groups of links being spaced apart centrally of the tape, and each group of links on said tape unit comprising one of the link chains of a complete fastener.
14. In separable fasteners employing opposed link chains adapted to be coupled and uncoupled by a slider movable along said chains, a chain forming unit comprising an elongated tape, said tape having two groups of double acting links arranged longitudinally of one edge portion thereof, said groups of links being spaced apart centrally of the tape, each group of links on said tape unit comprising one of the link chains of a complete fastener, and means forming end stops on the unit adjacent the ends of said chains.

LOUIS H. MORIN.
